UNITED STATES PATENT OFFICE

124,873

DESIGN FOR A TEXTILE FABRIC

Andre Proteau, New York, N. Y.

Application December 10, 1940, Serial No. 97,231

Term of patent 3½ years

To all whom it may concern:

Be it known that I, Andre Proteau, a citizen of the Republic of France, residing in the city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design.

The design unit is contained between the dot and dash lines, which unit is repeated in regular succession, and indicated by the extensions beyond the unit boundaries.

I claim:

The ornamental design for a textile fabric, substantially as shown and described.

ANDRE PROTEAU.
